UNITED STATES PATENT OFFICE.

EDWARD J. FUCIK, OF CHICAGO, ILLINOIS, ASSIGNOR TO GREAT LAKES DREDGE AND DOCK COMPANY, OF CHICAGO, ILLINOIS, A CORPORATION OF NEW JERSEY.

FENDER FOR DOCKS.

1,270,810.

Specification of Letters Patent.

Patented July 2, 1918.

Application filed February 24, 1917. Serial No. 150,682.

To all whom it may concern:

Be it known that I, EDWARD J. FUCIK, a citizen of the United States, residing at Chicago, in the county of Cook and State 5 of Illinois, have invented certain new and useful Improvements in Fenders for Docks, of which the following is a specification.

My invention relates more particularly to fenders for protecting concrete construction 10 from the impact of vessels. Prior to this invention concrete docks and the like have been provided with a beam of wood running along the face thereof at a suitable elevation to prevent immediate contact between boats 15 landing at the dock and the concrete. These beams have been rigidly secured to the face of the dock or in some instances partially embedded therein so as to practically form a part of the dock. While they serve their 20 purpose to an extent they are open to the very serious objection that being rigid with the dock they immediately transmit a strain to the latter along the line of the beam, and if the strain is sufficiently great it results in 25 cracking the concrete structure. Furthermore, when the beam becomes substantially worn out by the abrasion and pounding which it receives from the sides of vessels, it requires replacement, which is difficult 30 and expensive by reason of its being secured to or embedded in the concrete. A further objection to this form of fender is that when 35 a vessel comes in contact therewith it subjects the latter to a severe strain along a horizontal line which the vessel is not well adapted to withstand.

It is the object of my invention to provide a mat, or series of mats, of suitable area suspended along the face of the dock in such 40 manner that they may have a certain movement relative to the dock to yield somewhat to the movement of a vessel parallel to the face of the dock, and therefore save the latter from this strain, and to distribute the 45 force of the impact of the vessel over a large area of the dock and of the side of the vessel whereby injury to either is avoided.

In the accompanying drawing I have shown and in the following specification 50 described a preferred form of my invention. It is to be understood, however, that the specific disclosure is for the purpose of ex-

emplification only, and that the scope of the invention is defined in the following claim in which I have endeavored to distinguish 55 it from the prior art so far as known to me without, however, relinquishing or abandoning any portion or feature thereof.

Referring to the drawings, Figure 1 is a face view of a portion of a dock showing 60 my invention applied thereto; and Fig. 2 is a cross-section of the same.

The dock 3 is shown, and may be of ordinary concrete construction, with eye-bolts 4 embedded in the upper face thereof at suitable intervals for the purpose to be described. From each eye-bolt is suspended a mat 5 of suitable area formed of lumber which is suspended from the eye-bolt by means of a steel cable 6. For ordinary purposes a mat eight feet square has been found desirable, and is preferably composed of three layers 7, 8, 9, of good hard wood, arranged with the grain crossing and secured together at short intervals by spikes or the like. I have found it to be satisfactory to make the layers of oak planking four by twelve inches, and of a length depending upon the dimensions of the mat. The ends of the cable 6 are anchored to the mat by eye-bolts 10 which preferably extend completely through the mat as shown.

While I have described a preferred construction of the mat, it will be obvious that many of the advantages of my invention 85 may be secured without following the details set forth as to the dimensions and arrangement of the timbers incorporated in the mat, the means for suspending it from the dock, etc. The number of these mats 90 and the distance apart along the face of the dock will depend upon the character of service that they are called upon to perform. It will be seen that the construction is particularly adapted to avoid lateral strain and 95 to so distribute strains due to direct impact as to avoid injury to the dock and to the vessel concerned. The fender may be readily constructed by unskilled labor, of common materials, and is easily installed and replaced, and by reason of its form and the distribution of strain it is not so readily worn out as are the constructions heretofore in use. Because of the fact that the fender 100

does not, as in former devices, form a part of the dock structure and is not embedded therein, when worn out it may be discarded and readily replaced at low expense.

5 I claim:

A fender for docks and the like consisting

of a large rectangular mat composed of a series of layers of timbers, the grain of the adjacent layers being at an angle to each other, and means for suspending the fender 10 against the face of a dock.

EDWARD J. FUCIK.
